UNITED STATES PATENT OFFICE.

WILLIAM F. WEBB, OF GARDEN CITY, KANSAS, ASSIGNOR OF ONE-HALF TO ELBERT A. ORR, OF GARDEN CITY, KANSAS.

ENGINE-STOPPING DEVICE.

1,387,746.

Specification of Letters Patent. Patented Aug. 16, 1921.

Application filed April 5, 1920. Serial No. 371,340.

To all whom it may concern:

Be it known that I, WILLIAM F. WEBB, a citizen of the United States, residing at Garden City, in the county of Finney and State of Kansas, have invented certain new and useful Improvements in Engine-Stopping Devices; and I do declare the following to be full, clear, and exact description of the invention, such as will enable others skilled in the art to which it appertains to make and use the same.

My invention relates to automatic stopping devices for automobiles and other engines and more particularly to a pressure-controlled device for cutting off the current to the spark plugs in case the oil in the lubricating system recedes a dangerous amount below normal.

The principal object of the invention is to provide an extremely simple and inexpensive, yet a reliable device for producing the required results, and one which may be easily installed in connection with numerous types of engines.

Another object is to make novel provision for manually setting the device in engine-running position, this being necessary for starting since when the engine is standing idle, the oil pressure is not up to normal and consequently the invention then stands in engine-stopping position. This manual setting may also be used if it is necessary to continue running the engine after it has automatically stopped.

With the foregoing and minor objects in view, the invention resides in the novel construction and arrangement of parts herein-after described and claimed, the descriptive matter being supplemented by the accompanying drawings.

Figure 1 is a diagrammatic view showing the application of my invention to a battery ignition system for internal combustion engines.

Fig. 2 is an enlarged vertical section of the controlling switch and its operating means.

Figs. 3 and 4 are respectively vertical and horizontal sections as indicated by lines 3—3 and 4—4 of Fig. 2.

Fig. 5 is a detail elevation showing more particularly the key which is used when

manually setting the device in engine-running position.

On Sheet 1 of the drawings, I have shown the application of my invention to a well known form of battery ignition for an internal combustion engine E. This ignition system includes the usual timer T, coil C, vibrator V, distributor D, battery B, and switch S. As usual in systems of this character, the primary circuit passes through the vibrator V, coil C, and timer T and then returns to the battery, while the secondary or high tension current travels to the distributor D, from such distributor to the spark plugs, across the spark gap to the ground and returns from such ground to the battery. I have shown my improved engine stopping device included in the primary circuit and so arranged as to break this circuit when the pressure of oil in the oil line O diminishes to a dangerous degree. The oil is pumped from the usual crank case or reservoir through the oil line by means of an appropriate pump P, and in order to prevent pulsation of the oil during its travel through the line O, which pulsation would interfere with proper operation of the engine stopping device, I provide an air chamber A which is in communication with the oil line.

Incorporated in the primary circuit of the ignition system are relatively movable and fixed switch members 1 and 2, such members being coöperable in forming a switch for either placing the ignition system in condition for running the motor or for stopping the same. In the present showing, the two members 1 and 2 normally complete the circuit and they are held in contact by means of a stem 3 actuated by a diaphragm 4 located in an appropriate casing 5, said casing being in communication with the oil line O. As long as the engine E is operated and the pump P is supplying the required quantity of oil through the line O, the pressure of such oil against the diaphragm 4 will cause the stem 3 to hold the movable switch member 1 in operative contact with the relatively fixed member 2. The moment the oil supply is fully exhausted however, as to cause the pump P to supply an inadequate quantity through the line O, pressure in the casing 5 decreases, with the result that the stem 3

moves inwardly and allows the movable switch member 1 to recede from the member 2. The primary circuit of the ignition system is thus broken with the result that 5 the engine is brought to a standstill.

Since the pump P is not operating when the engine stands idle and consequently there is no oil pressure to hold the switch members 1 and 2 in engagement with each 10 other, it is necessary to provide some adequate means whereby said members may be manually engaged, in order that the motor may be started. This manual operating means may of course vary, but I prefer that 15 it shall be in the form of a cam 6 as shown.

Fig. 1 of the drawings merely shows the parts 1 to 6 in diagram in order to illustrate their proper relation with the battery ignition system of an internal combustion engine, while on Sheet 2 of the drawings the detailed construction of the several features is fully illustrated. Consequently, in the following description, reference is made to Sheet 2 only.

25 For supporting the parts 1 to 6, I employ an appropriate plate 7 having several arms 8 extending in the same direction therefrom, the outer ends of these arms serving as carrying means for the casing 5, which casing 30 is secured thereto by bolts 9 or any preferred means. One of the arms 8 carries the relatively fixed switch member 2, while another of said arms supports the relatively movable member 1. Both of these members are preferably in the form of L-shaped strips of 35 spring metal connected with the arms 8 by suitable binding posts 10 which are shown insulated from said arms as indicated at 11. The arms 1 and 2 are provided with co-acting 40 platinum points 12 or other suitable contacts and the stem 3 normally thrusts against an insulator 13 carried by the arm 2, so that the aforesaid contacts are forced into engagement with each other as depicted clearly 45 in Fig. 2. The moment the oil pressure in the casing 5 recedes below normal, however, the resiliency of the switch arm 1 preferably, assisted by a coiled spring 14 acting on the diaphragm 4, causes the switch to 50 open to break the ignition circuit, thereby stopping the motor.

I have shown an adjusting screw 15 threaded through the plate 7 for the purpose of adjusting the switch member 2 toward 55 the member 1 for properly relating the contacts 12 whenever this is necessary. As shown, the screw 15 bears against the lower end of an insulating plate 16 which is secured to the aforesaid switch member 2, and 60 in the present showing, the cam 6 acts against said plate for the purpose of springing the member 2 into contact with the arm 1, prior to projection of the stem 3 by the oil pressure, thereby allowing the 65 motor to be started or permitting running

of said motor after it has been automatically stopped. I prefer to mount the cam 6 on the end of a shaft or stem 17 which passes rotatably through the supporting plate 7 and through an appropriate escutcheon plate 18. The two plates 7 and 18 may well contact with opposite sides of the dash of an automobile and I prefer to provide screws or the like 19 for clamping them tightly in place. The adjusting screw 15 70 preferably passes through the plate 18 and is thus readily accessible, and said screw also serves as a stop to limit the turning movement of the key 20 which is used for turning the shaft 17 for the purpose of setting the cam 6. The key 20 preferably abuts the screw 15 when the engine is running with the several parts of the controlling device related as shown in Fig. 2, and the proper amount which said key must be 75 turned to manually set the device in engine-running position, may well be indicated on the plate 18 as shown for instance at 21.

The device may be easily installed in connection with numerous forms of motors, 80 whether battery or magneto ignition be used, and in either case the operation of the instrument will be highly sensitive to a drop in the oil pressure. Whenever such a drop occurs with the motor running, the ignition circuit 85 is so affected as to bring the motor to a stand still, thereby preventing the possibility of injury through lack of lubrication. If it is absolutely necessary to continue running the motor after it has been automatically 90 stopped, the key 20 may be actuated to force the relatively fixed switch member 2 into contact with the member 1, thus permitting the ignition system to again operate. The parts may remain in this position until a 95 point is reached at which the oil supply may be replenished, and after refilling the oil reservoir, the key 20 should be again returned to its normal engine-running position, so that the switch may again automatically operate 100 whenever necessary.

With the motor standing idle, there is insufficient pressure in the oil line O to project the stem 3 and close the switch. It is therefore necessary to operate the key 20 to bring the two switch members 1 and 2 into engagement, before the engine can be started. The moment such starting has been effected however, the key 20 should be returned to its normal position in order that the switch may 115 automatically interrupt the supply of current to the spark plugs whenever the oil pressure recedes to a dangerous degree.

From the foregoing, taken in connection with the accompanying drawings, it will be 120 seen that although my invention is of comparatively simple and inexpensive nature, it will be highly efficient and in every way desirable and since probably the best results 125 may be obtained from the details disclosed, 130

such details may well be followed. I wish it understood, however, that within the scope of the invention as claimed, considerable latitude is allowed for making such changes as 5 occasion may dictate.

I claim:

1. An engine stopping device comprising a support, relatively fixed and movable switch members mounted on said support and forming an engine controlling switch, a case mounted on said support and adapted for communication with a liquid circulating system of the engine, a stem extending slidably from the interior of said casing for 10 moving said movable switch member to engine-running position and holding it normally in such position, and a pressure operated device in said casing acting on said stem to normally hold the latter in position 15 to hold said switch in engine-running position.
2. An engine-stopping device comprising a supporting plate having arms extending from one side, a relatively fixed switch arm 20 mounted on one of the aforesaid arms, a movable switch arm mounted on another of said arms for co-action with said relatively fixed switch arm in forming an engine stopping switch, a casing mounted on said arms 25 of the supporting plate and adapted for communication with a liquid circulating system of an engine, a pressure operated device in 30 said casing, and a stem extending from said device to said movable switch arm for holding the latter in engine-running position.
3. An engine stopping device comprising an engine controlling switch, means for hold- 35

ing said switch in engine-running position, said means being adapted for operation by pressure in a liquid circulating system of the 40 engine, and manually operated means independent of the aforesaid holding means, for holding said switch in engine-running position when starting.

4. An engine-stopping device comprising 45 relatively fixed and movable switch members, means for moving said movable switch member into engine-running relation with the relatively fixed member, said means being adapted for operation by pressure in a liquid 50 circulating system of the engine, and manually operable means for moving said relatively fixed member into engine-running relation with said movable member before movement of the latter by its 55 operating means.

5. An engine-stopping device comprising a support, relatively fixed and movable switch members mounted on said support and forming an engine-stopping switch, means 60 mounted on said support for moving said movable switch member into engine-running relation with said relatively fixed member, said means being adapted for operation by pressure in a liquid circulating system of the 65 engine, a manually rotatable stem mounted on said support, and a cam on said stem for moving said relatively fixed member into engine-running relation with said movable member before movement of the latter by its 70 operating means.

In testimony whereof I have hereunto set my hand.

WILLIAM F. WEBB.
